UNITED STATES PATENT OFFICE.

HERMANN BUSCH, OF KIEL, GERMANY.

CLOTHES HANGER.

Application filed January 20, 1915. Serial No. 3,412.

To all whom it may concern:

Be it known that I, HERMANN BUSCH, a citizen of Germany, residing at Kiel, Germany, have invented certain new and useful 5 Improvements in Clothes Hangers, of which the following is a specification.

Clothes hangers such as have been generally used heretofore, consisting simply of a bent-wire suspension hook and a garment-10 receiving cross-piece or bar, have the disadvantage that they are awkward to handle. Particularly where large numbers of these hangers are used, such as for example in clothing stores, is this disadvantage an item 15 of importance. The employees of such stores are inclined to seize the clothes on such hangers by gripping the hanger, not by the hook but by the wooden or other cross-piece, since gripping the hook would 20 be very inconvenient and would also easily lead to injuries to the hand or fingers. Since the wooden or other cross-piece of the hanger is covered by the respective garment, the repeated gripping of the garment at the 25 same place is quite likely to injure it to a considerable extent.

It has been proposed to obviate these disadvantages by bending the portion of the wire, which leads from the garment supporting bar directly to the suspension hook portion, into a loop to form a handle by which the complete hanger may be conveniently seized or carried. This arrangement has 30 not been satisfactory in practice because, especially in the case of heavy clothing, the full weight of the clothing is borne by and deforms the loop handle.

The present invention is directed toward overcoming this latter difficulty; and to this 40 end I bend a wire in such manner as to form, in addition to a stem or shank portion what are in effect two sections each of which has an independent function to perform, one acting as the suspension hook and the other 45 as the carrying handle. The stem or shank portion extends from the garment supporting bar and continues into a hook portion, the wire continuing from the outer end of the hook portion into a handle portion, from 50 which the wire then returns substantially to the stem portion, with respect to which it is rigidly fixed, as for example, by being anchored in the cross bar in which the stem portion is anchored. In this construction, 55 with the two ends of the wire being anchored with respect to each other, deflection of the

hook portion is resisted not only by the stiffness of that portion of the wire but also by the wire which forms the handle portion, and similarly the hook portion assists in 60 opposing a bending strain applied to the handle portion. Since the hanger is practically always suspended when in use, it follows that the handle portion is subjected to stress only for relatively limited periods, 65 and I have found in practice that this stress is not sufficient to deform or distort the handle when the wire used therein is of only the usual strength.

In the accompanying drawings, in Figs. 70 1 to 10 inclusive, I have shown a number of specific forms in which my invention may be embodied in practice.

In each of these figures the hanging or suspension hook portion has been designated by the letter *a*, and the carrying handle portion by the letter *b*. The wire, it will be noted, extends upward from the cross-piece *c* to the point *a* where it is bent into the form of a hook. The wire is then 75 bent back upon itself into the form of a handle *b*; and, in the specific embodiments 80 of the invention shown, is then continued on back to the cross-piece *c*. By this construction hook and handle portions are provided 85 which are independent of each other in the sense that they are separately engaged when the garment is hung or carried and at the same time, by reason of the hook and handle portions being located between two 90 portions of the wire which are rigidly fixed with respect to each other, the hook portion 95 is reinforced by the material of the handle portion and vice versa. Since the wire is bent back upon itself at the edge or mouth of hook *a*, sharp points are eliminated there. As shown in Fig. 8, the two 100 ends of the wire may be twisted before their entry into the wooden cross-piece in order to anchor the wire leading from the handle portion to the shank or stem, and thus provide a more rigid fixture. In Fig. 10, the carrying handle portion is provided with padding; this modification is especially 105 adapted for use with heavy garments.

I claim:—

1. A garment hanger suspending and handle portion comprising a length of wire formed with a stem portion continued into a hook portion, and from the outer end of the hook portion continuing into a handle portion, and from the handle portion re-

turned to the stem portion and rigidly anchored with respect thereto, to enable the bending resistance of the handle portion to assist in opposing the bending of the hook portion and vice versa.

2. A garment hanger suspending and handle portion comprising a length of wire formed with a stem portion, a hook section and a handle section, the wire of said stem portion continued into one of the two said sections and from that to the other of said sections and returning from the latter to the said stem portion and anchored with respect thereto.
- 10 3. A garment hanger suspending and handle portion comprising a length of wire forming at one end a stem portion, continuing from the upper end of the stem portion into and through a curved hook portion, and from the outer end of the curved hook portion upwardly and across above the hook portion to form a handle portion
- 15 4. A garment hanger suspending and handle portion comprising a length of wire forming at one end a stem portion, continuing from the upper end of the stem portion into and through a curved hook portion, and from the outer end of the curved hook portion upwardly and across above the hook portion to form a handle portion
- 20

and then downwardly to a point adjacent to the stem portion and rigidly fixed with respect thereto.

25

4. In a garment hanger a suspending and handle portion comprising a length of wire forming at one end a stem portion, continuing from the upper end of the stem portion into and through a curved hook portion, and from the outer end of the curved hook portion upwardly and across above the hook portion to form a handle portion and then downwardly to a point adjacent to the stem portion and rigidly fixed with respect thereto, all parts formed by the wire being disposed substantially in the same plane.
